UNITED STATES PATENT OFFICE

90,845

DESIGN FOR A CHANDELIER

Harry J. Gruber, New York, N. Y.

Application July 22, 1933. Serial No. 48,795

Term of patent 7 years

To whom it may concern:

Be it known that I, HARRY J. GRUBER, a citizen of the United States, residing at No. 175 West 76th Street, city of New York, county of New York and State of New York, have invented a new, original, and ornamental Design for a Chandelier, of which the following is a specification, reference being had to the accompanying drawing forming part thereof.

The figure is a perspective view showing my chandelier.

I claim:

The ornamental design for a chandelier, as shown.

HARRY J. GRUBER.
